UNITED STATES PATENT OFFICE.

JAMES FRYE, OF PHILADELPHIA, PENNSYLVANIA.

SHAVING-CUP.

SPECIFICATION forming part of Letters Patent No. 568,529, dated September 29, 1896.

Application filed June 1, 1896. Serial No. 593,700. (No model.)

To all whom it may concern:

Be it known that I, JAMES FRYE, a citizen of the United States, residing at Philadelphia, in the city of Philadelphia and State of Pennsylvania, have invented certain new and useful Improvements in Shaving-Cups; and I do declare the following to be a full, clear, and exact description of the invention, such as will enable others skilled in the art to which it appertains to make and use the same, reference being had to the accompanying drawings, and to the letters of reference marked thereon, which form a part of this specification.

My invention relates to new and useful improvements in shaving-cups, as fully described hereinafter and pointed out in the claims hereunto annexed.

Referring to the drawings, Figure 1 is a vertical section of a shaving-cup embodying my improvements, the section being taken on the line 1 1 of Fig. 2. Fig. 2 is a plan view of the construction shown in Fig. 1. Fig. 3 is a vertical section similar to that shown in Fig. 1, but of a somewhat modified form of my invention; and Fig. 4 is a plan view of the construction illustrated in section in Fig. 3.

Similar letters of reference refer to similar parts throughout the several views of the drawings.

30 A is a cup, preferably formed of metal, the same being internally threaded at the top for the reception of the flanged portion of the cup B, although, if desired, the two portions A and B may be united together by soldering, or in any other desired manner. A screw-plug B' is fitted to an opening in the flanged portion of the inner cup B at the top of the shaving-cup, said opening being provided for the purpose of filling the annular space formed 40 between the cups A and B with water.

To the cup A is secured a handle A', and retained within said handle is a rubber bulb C, one end of which communicates with an opening provided with a valve c, and the other with an opening provided with a valve c' at the top of the handle.

A pipe C' communicates with the opening in the top of the handle and thence passes through the flanged portion of the cup B, the whole being so arranged that by compressing the bulb C a volume of air is forced into the annular space between the cups A and B, so

that a portion of the water contained therein will be forced through the pipe D and discharged at the mouth E' of said pipe into the center of the cup B, which may contain soap for forming lather. In the construction shown in Figs. 3 and 4 the screw-plug B' and the bulb C, with the connecting parts already described, are omitted, the annular space between the cups A and B being supplied with a quantity of water which will pass through the opening D², and when said space has been filled the excess of water contained in the cup B is poured out. In order to then supply the cup B with a quantity of water from the annular space, I provide an opening in the flanged portion of said cup with a valve C², forming part of a lever E, which is fulcrumed at a point e and held in a closed position by a leaf-spring e'. When the short arm of the lever E is depressed, the valve C² is raised from its seat, allowing air to enter the annular space, which allows the water to flow by gravity through the opening D into the inside of the cup B.

Having now described my invention, what I claim, and desire to secure by Letters Patent, is—

1. A shaving-cup comprising an outer receptacle and an inner receptacle, said inner receptacle having a flanged top adapted to be detachably secured to the outer cup, an annular space formed between said cups and adapted to be filled with water, an inlet for air in the flanged portion of the inner cup and an outlet for water at the bottom of the inner cup, and a valve for regulating the quantity of air admitted to the annular space, substantially as specified.

2. A shaving-cup comprising an outer receptacle and an inner receptacle, said inner receptacle having a flanged top adapted to be detachably secured to the outer receptacle, a collapsible bulb secured within a handle mounted upon the outer receptacle, a passage leading from the top of bulb to the annular space between the receptacles and provided with a valve, a valved opening in the lower portion of said bulb, and a pipe located in the annular space and having an outlet at the top of the inner cup to which it is secured, substantially as specified.

3. The combination in a shaving-cup of an

outer receptacle A, and an inner receptacle B, the inner receptacle having a flanged top adapted to be secured to the outer cup, a handle A' mounted upon the outer receptacle and provided with a collapsible bulb C a pipe C' communicating with the upper part of said bulb and the annular space between said receptacles and provided with a valve c', a valve c provided at the lower end of said bulb, a pipe D secured to and having an opening

into the inner receptacle at the top thereof, and an opening provided with a screw-cap B' at the top of the shaving-cup, substantially as specified.

In testimony whereof I affix my signature 15 in presence of two witnesses,

JAMES FRYE.
